SHINGLE

Harry H. Honigbaum, Forest Hills, N. Y.

Application October 20, 1934, Serial No. 749,293

9 Claims. (Cl. 108—7)

This invention relates to shingles and is particularly intended for use in the manufacture of shingles from composition roofing material, although not necessarily limited to this material. Furthermore the invention is especially directed to the economical manufacture and laying of individual shingles of novel and unique construction, and so constituted as to give a maximum covering for a minimum amount of material and efficiently distributed.

An important feature of the invention from the standpoint of the method is inherent in the fact that the present shingle may be cut from yard material without waste and in a progressive manner well adapted to manufacturing purposes.

From the standpoint of the shingle, as an article of manufacture, an important feature of the invention resides in the fact that it has unusual covering capacity for a minimum amount of material and may be laid expeditiously and in one of its practical forms with absolute accuracy as to overlap and placement with respect to shingles of an underlying course as well as with respect to shingles of the same course.

The shingle of this invention is characterized by its substantially L-shaped configuration and the desirability of this general contour to a wide diversity of shapes in the weather edge of the shingle, thereby permitting it to be used on a roof in a great variety of patterns.

Another feature of the invention resides in the provision of novel and efficient means for alining the shingles with respect to one another and to shingles of the preceding course by forming each shingle with abutments adapted to cooperate with abutments of other shingles during the laying thereof in a manner to give absolute accurate alinement in an automatic way and without necessitating the use of extraneous gauges or measuring devices.

A further feature of the invention resides in the formation in the body of the shingle of locking devices at the weather edge thereof adapted to cooperate with similar shingles of an underlying course in such a way as to hold down the weather edge of the shingle and to preclude the same from flapping in the wind.

Features of the invention, other than those specified, will be apparent from the hereinafter detailed description and claims, when read in conjunction with the accompanying drawings.

The accompanying drawings illustrate different practical embodiments of the invention, but the constructions therein shown are to be

understood as illustrative, only, and not as defining the limits of the invention.

Figure 1 shows the manner of laying a roof with shingles embodying the present invention.

Figures 2, 2a and 2b shows the manner of practising the present invention in the cutting of shingles from yard material.

Figures 3, 3a, 3b, 4, 4a, 4b, 5, 5a and 5b show the application of the method to shingles of somewhat different shape from those illustrated in Figures 1 and 2.

Figures 6, 7 and 8 show the manner in which the shingle of this invention may be provided with locking and spacing devices of various kinds within the scope of this invention.

Figure 9 shows a plurality of shingles laid in two courses with the interlocking spacing and alining devices cooperating with one another.

Figures 10-14 show different locks which I may employ at the weather edge of the shingle to hold down the weather edge against flapping in the wind.

In practising the method of this invention, in one of its practical forms, I cut shingles from composition roofing material fed from the roll by the yard. In so doing, I make transverse cuts 2, a longitudinal cut 3 and additional broken line cuts 4, as indicated in dotted lines in Figure 2. The actual placement of these various cuts will of course depend upon the sizes of the shingles and the width of the material 1, but in any event the cuts 2 and 3 divide the area of the strip 1 into rectilinear areas while the broken line cut 4 divides these rectilinear areas into two L-shaped shingles fitted about one another. These shingles are cut progressively from the end of the strip 1 with lines 2, 3 and 4 cut in any desired succession, so that in any event the shingles are cut progressively from the end of the strip by any appropriate cutting mechanism to be freed from the strip as indicated at 5 and 6 in Figures 2a and 2b. In the shingles of this figure, each shingle is L-shaped and somewhat wider than its height. If desired, however, the height and width of the shingle may be the same as indicated in Figures 3, 3a and 3b in which event the cuts will be accomplished as shown in Figure 3.

In the shingles of Figures 2, 2a and 2b and 3, 3a and 3b, the weather edge of the shingle is straight, but if it is desired to have the corners cut off, additional cuts 7 may be made during the process of cutting the shingle from the strip 1, as indicated in Figures 4, 4a and 4b. If an ornamental edge such as a wavy or corrugated edge is desired, the transverse cuts 2 may be

so configurated as indicated at 8 in Figures 5, 5a and 5b and it will of course be understood that the actual configuration of these cuts may be varied within wide limits to produce weather edges shaped as may be desired. In any event the method is the same. The transverse longitudinal and broken line cuts serving in each instance to separate from the strip a rectangular portion thereof and to subdivide such rectangular portion into complementary L shaped shingles of identical form. A marked advantage of this arrangement is that the shingle may be made progressively by appropriate cutting machinery without any waste and in an expeditious manner.

L shaped shingles made in accordance with this invention may be conveniently laid, as shown in Figure 1, in overlapping courses and in such manner that the joints between shingles of each course will overlie the upstanding portion of the shingles of the next underlying course to thereby provide against leakage while giving a satisfactory overlap throughout. The amount of the overlap will of course depend upon the size of the shingle and the portion of the shingle laid to the weather, but I find it convenient in practice to lay them with uniform overlap which may conveniently amount to 2 inches or more in all directions. The resulting roof will be tight in that it will exclude rain water and the laying may be expeditiously carried out because of the somewhat wide dimension of the shingle at the butt or weather edge.

In the description as thus far advanced, the shingles are laid as illustrated in Figure 1 and suitably nailed in place to a roof without any interlocking or interfitting, the workmen serving to position the shingles according to his best ability for the purpose of obtaining uniformity in appearance. The present invention, however, provides for devices for interlocking the shingles in a manner to facilitate the laying thereof and to hold down the weather end against flapping in the wind.

Figure 6 shows such a shingle. The general outline contour of the shingle may be as shown in any of the preceding figures and the said devices consist in cutting or forming the shingle within its margin for the purposes stated. To this end, the upper edge of the upright or vertical part of the shingle is provided with a cut out or slit 9 preferably so shaped as to provide a hooked tab 10 which constitutes an abutment while the upper edge of the horizontal part is provided with a notch 11. The lateral free edge of the upright part is also provided with a notch 12 and above the same is a hook shaped tab 13 forming another abutment. The lower edge of the horizontal part, i. e., the weather edge is provided therein with cut outs or slots 14 spaced apart from one another and so shaped as to form between them a retainer 15. The slots 14 and resulting retainer 15 may be of a wide variety of shapes, illustrative forms of which are shown in Figures 10-14. In any event, however, a retainer is so constituted that it may be passed through the space between adjacent shingles of an underlying course with lateral portions of the retainer hooked under adjacent shingles of the latter course to hold down the weather edge 16 of the shingle on which it is formed. The manner in which the retainer 15 interfits with underlying shingles is clearly shown in Figure 9 from which its use will be apparent.

When laying shingles with the interfitting and

alinining devices shown in Figure 6, the retainer 15 of each overlying shingle fits under the edges of two underlying shingles, as shown in Figure 9, while the notch 12 is engaged by the hook shaped tab 10 of one of such underlying shingles and the notch 11 is engaged by the hook shaped tab 13 of the other underlying shingle as clearly shown in Figure 9. By engaging the parts 10 and 12 and 11 and 13 as illustrated, the overlying shingle is accurately positioned with respect to the underlying shingles as well as accurately spaced with respect to shingles of the same course of which it forms a part and furthermore the positioning of each overlying shingle is insured so that joints will be broken at the vertical or upstanding part of the underlying shingles to provide for proper overlap.

If desired some of the advantages obtained in the shingle of Figure 6 may be had without necessarily employing all. For example, I may dispense with the retainer 15 and utilize the shingle as shown in Figure 7, or I may dispense with the parts 10-13 and use merely the retainer 15, as shown in Figure 8, or as a further modification, I may dispense with all of these parts and use a shingle, as shown in Figures 1-5b. In practice, however, I prefer to use all of the retaining and spacing devices which I have described as they materially facilitate the laying of the shingle and at the same time tie down the weather edge of each shingle individually.

The shingle of this invention will cover maximum surface with minimum material and without waste either in the manufacture or in the laying.

The foregoing detailed description sets forth the invention in its preferred practical form, and the invention is to be understood as fully commensurate with the appended claims.

Having thus fully described the invention, what I claim as new and desire to secure by Letters Patent is:

1. As a new article of manufacture, a shingle of roofing material having a contour substantially L shaped, an abutment in the vertical portion of the shingle and adjacent one lateral edge of the shingle, and another abutment formed in the upper edge of the vertical portion of the shingle in spaced relation to the lateral edges of said vertical portion, said abutments being adapted for engagement with edges of shingles of the same kind to facilitate alinement of the shingles when a plurality of said shingles are laid in courses on a roof.

2. As a new article of manufacture, a shingle of roofing material having a contour substantially L shaped, an abutment in the vertical portion of the shingle and adjacent one lateral edge of the shingle, and another abutment formed in the upper edge of the vertical portion of the shingle in spaced relation to the lateral edges of said vertical portion, and additional abutments formed in the upper edge of the horizontal portion of the shingle and in the vertical lateral edge of the vertical portion of the shingle, all of said abutments adapted to cooperate with abutments formed in shingles of the same kind when a plurality of such shingles are laid in courses on a roof, for the purpose of insuring uniform overlap between courses and alinement and lateral spacing of shingles of the same courses.

3. As a new article of manufacture, a shingle of roofing material having a contour substantially L shaped, an abutment in the vertical portion of the shingle and adjacent one lateral edge of the

shingle, and another abutment formed in the upper edge of the vertical portion of the shingle in spaced relation to the lateral edges of said vertical portion, and additional abutments formed in the upper edge of the horizontal portion of the shingle and in the vertical lateral edge of the vertical portion of the shingle, all of said abutments adapted to cooperate with abutments formed in shingles of the same kind when a plurality of such shingles are laid in courses on a roof for the purpose of insuring uniform overlap between courses and alinement and lateral spacing of shingles of the same courses, and retainers formed from the horizontal portion of the shingle adjacent the weather edge thereof to extend between and beneath shingles of an underlying course when a plurality of such shingles are laid in courses on a roof.

4. As a new article of manufacture, a shingle 20 of roofing material having a contour substantially L shaped, a hook shaped tab cut from the vertical portion of the shingle and at one lateral edge of the shingle, a notch formed in the same edge of the shingle below the hook shaped tab, another hook shaped tab formed in the upper 25 edge of the vertical portion of the shingle in spaced relation to the lateral edges of said vertical portion, and a notch formed in the upper edge of the horizontal portion of the shingle, the notch in the vertical edge of the shingle being adapted to engage with the hook shaped tab in the upper edge of another shingle of the same kind when a plurality of such shingles are laid in courses on a roof and the notch in the upper 30 edge of the horizontal portion of the shingle being adapted to be engaged by the hook shaped tab in and adjacent the lateral edge of another shingle of the same kind when a plurality of such shingles are laid in courses as stated in order 35 to insure uniform overlap of shingles in various courses and lateral spacing and longitudinal alinement of shingles in the same course.

5. A roof embodying a plurality of L shaped shingles laid in courses with the shingles of each course breaking joints over the vertical portions of shingles of the next underlying course, each shingle being provided adjacent one of its vertical edges and both of its upper horizontal edges with interfitting cut out portions to insure uniform

overlap between the shingles of successive courses and lateral spacing and alinement between shingles of the same course.

6. A roof embodying a plurality of L shaped shingles laid in courses with the shingles of each course breaking joints over the vertical portions of shingles of the next underlying course, each shingle being provided at one of its vertical edges and both of its upper horizontal edges with interfitting cut out portions to insure uniform overlap 10 between the shingles of successive courses and lateral spacing and alinement between shingles of the same course and each shingle being provided adjacent its weather edge with retaining devices projecting between adjacent shingles of 15 the next underlying course and beneath such shingles to hold down the weather edge of the shingle on which the retainer is formed.

7. As a new article of manufacture, a shingle provided, within the upper portion of the body 20 thereof, with an abutment adjacent one lateral edge of the shingle and adapted to cooperate with a shingle of an underlying course, and another abutment within the lower portion of the body adjacent its weather edge and in spaced relation to the other lateral edge of the body and also adapted to cooperate with a shingle of said 25 underlying course.

8. As a new article of manufacture, a shingle provided in one of its lateral edges and in the 30 upper portion of the shingle with a cut out forming an abutment and adapted to cooperate with a shingle of an underlying course, said shingle also being provided within its lower portion adjacent its weather edge and in spaced relation to 35 its other lateral edge with another cut out forming another abutment and also adapted to cooperate with a shingle of said underlying course.

9. As a new article of manufacture, a shingle provided in the upper portion of one lateral edge 40 with a cut out forming an abutment, a retainer cut from the body of the shingle adjacent its weather edge and spaced from said lateral edge and projecting in the direction of the latter, said shingle also being provided at its upper edge with 45 a finger cut from the body of the shingle and spaced from said lateral edge.

HARRY H. HONIGBAUM.
